UNITED STATES PATENT OFFICE

MARTIN FOX, OF CHICAGO, ILLINOIS, ASSIGNOR TO THE SENG COMPANY, A CORPORATION OF ILLINOIS

DAVENPORT BED

Application filed March 31, 1926. Serial No. 98,709.

This invention relates to an article of furniture which is a davenport when closed, but in which the seat is made of sections so connected that when the upper one is raised and pulled outwardly, it draws a lower section upwardly to an elevated position flush with the outer section so that together, they will form a sleeping surface, substantially at the height of the seat.

10 Among the objects of the invention are to provide a structure of this kind which will be sufficiently low either as a seat or as a bed so that coil springs may be mounted on the folding sections to provide a more comfortable seat or sleeping surface; to provide means for raising the rear section and swinging it forwardly due to the action of the upper seat member; to counterbalance the weight of the sections so that they may be 15 easily operated in opening and closing them; to provide coil spring supports which position the springs at suitable levels so that a thin pad may be unfolded from the outermost section upon both of the sections to 20 form a suitable sleeping surface without the necessity of a thick mattress; and in general, to produce the construction herein shown and described.

25 In the accompanying drawings illustrating this invention;

Figure 1 is a side elevation partly in section, showing a davenport constructed in accordance with the principles of this invention and in open or extended position;

30 Figure 2 is a section as taken on the line 2-2 of Figure 1;

Figure 3 is a side elevation partly in section illustrating the position of the parts when they are folded or closed and the device used as a davenport; and

35 Figure 4 is a perspective of one of the end supports.

One of the difficulties encountered in making a coil spring davenport or day bed is to provide supporting frames for coils so that they may be folded one below the other within the davenport frame and will be mounted so that they will unfold to an aligned position without the coils in either case being so high from the floor or ground

that seating or sleeping surfaces will be uncomfortable or unsightly in appearance. A further difficulty is to provide such a structure which will be sufficiently low that a seat pad or a separate cushion can be supported by the uppermost coil section when in use as a davenport, without being unsightly or uncomfortable.

Referring now more particularly to the drawings, a davenport frame 1 of any suitable construction is provided in which there may be an upholstered back 2 and ends 3 with connecting front and back supports 4 and 5. The ends and back of such a frame are usually made separately and they are 45 set up and connected before the folding seat structure is applied thereto.

The coil supporting means comprises front and rear sections 6 and 7 preferably made of angle irons and each comprising a rectangular frame within which is a spring supported fabric 8 upon which the coil springs 9 are secured and supported. The coil springs of each section are commonly fastened and tied together at top and bottom 50 so that they will be upheld in a substantially vertical position. The coil spring may be encased or enclosed by means of a fabric cover 10 or any other suitable means or they may be left open and have connected tops 55 only encased or enclosed by a thin covering 11. If desired, they may be left entirely uncovered, being joined and upheld simply by the top connecting means which may be of wire or fabric.

In order to support the frame sections 6 and 7 in the ends of the davenport frame 1, a cross piece 12 is provided for each end of the davenport frame having standards 13 and 14 at the front and rear ends thereof. 60 Pivotedly mounted in the cross piece are angular members 15 and 16 connected by a link 17 which makes them operate in unison, the end 18 of one of the members extending beyond its pivot in the cross piece and having 65 attached thereto a link 19 for moving the members 15 and 16 in unison. The upper part of these members 15 and 16 are pivoted 70 slidably in slots 21 and 21 provided in the end piece of the rear frame 7. Also pivotal- 75

ly and directly connecting the cross piece 12 and each end of the rear frame 7 is a link 22 which has a fixed pivotal connection with each of these parts, such that the movement 5 of the pivoted ends of the members 15 and 16 in their respective slots 20 and 21 is controlled. In other words, the members 15 and 16 are at one end of the slots in raised position, as shown in Figure 1, and they are 10 moved by the link to the other end of the slots in the lowermost position as shown in Figure 3. The result of this is that the amount of forward swing of the rear section 7 is controlled by the length of the pivoted 15 links 22. In this way the rear section 7 may be made to approach the front section 6 and nearly as desired in their open or expanded position.

To mount the frame 6 in the davenport 20 frame, levers 23 are mounted in the cross pieces 12 at the opposite ends of the frame which are affixed to a connecting shaft 24 so that they will operate in unison. These levers 23 are bent or formed to extend over 25 the standards 13 at the ends of the cross pieces 12 and to engage the shoulder 24' of the standards to limit the swinging movement of the levers and consequently of the outer section 6. Attached to the outer ends 30 of the levers 23 adjacent to their connection with the ends of the frame 6 are links 25, each of which is also pivotally connected to a support or foot 26 at the outer edge of the section 6 which automatically folds and 35 unfolds, depending upon the movement of this section.

The end pieces of the frame 6 are formed with extensions 6', to each of which a lever 27 is pivoted, the other end of the lever being 40 pivoted in its corresponding cross piece 12 and having an attached or integral toe 28, to which the link 19 is connected. The levers 27 and the levers 23 although of different shape 45 have substantially the same effective length, so that the upper section 6 as it is moved in and out of the frame is maintained in a substantially horizontal position.

In order to cushion or assist the folding and unfolding movements of the sections, a 50 spring 29 is attached at one end to a perforation 30 in the standard 13, and at the other end to a projection or toe plate 31 attached to or formed integrally with the toe plate 28. Another spring 32 is connected at one 55 end to the toe plate at 31 and at the other end to one end of a link 33, the other end of which is pivoted in the rear standard 14. The object of this connection is to allow a limited action of the spring 32 without placing 60 any tension, it being apparent that the spring 32 is in tension when the sections are opened as shown in Figure 1, and the spring 29 is in tension when the sections are closed as shown in Figure 3, the objects of the 65 springs being respectively to counterbalance

and to assist in the closing and opening operations.

From this construction, it is seen that the mounting for the front and rear sections 6 and 7 is entirely in the metal frame formed by the cross pieces 12 at the ends and in practice, the entire folding construction is manufactured and assembled complete, independently of the davenport frame construction. It is then necessary only to mount the folding construction in the davenport frame by attaching the cross pieces 12 and uprights 13 and 14 into the end frames of the davenport by means of bolts, screws or other suitable attaching devices.

In adapting this construction for use as a davenport it is customary to provide a front seat rail 34 supported by a brace 35 which is adapted to rest upon the front board 4 in the closed position with an upholstered edge 36 disposed above the rail 34 upon which is supported loose cushions or a sectional pad 37 which may be unfolded to rest upon the coil springs in their extended position, as shown in Figure 1.

To operate this construction, it is necessary only to grasp the upper or outermost section when in closed position as shown in Figure 3, and as it is counterbalanced by the spring 29 in this position, it is easy to unfold or extend the sections. The upper or outer section moves upwardly and outwardly on the levers 23 and 27, causing a corresponding movement of the rear section upon its members 15 and 16, the forward movement of which is limited by the links 22. The opening action places the springs 32 in tension, so that to close or fold the sections, it is necessary only to fold the sectional pad 37 in either direction so that it rests entirely upon one section, 6, or the other section 7, and then simply to raise the outer section 6 and swing it backwardly into the frame 1. It will be observed from Figure 3 that a sufficient space is provided between the upper and lower sections 6 and 7 in their folded position to dispose the sectional pad 37 therebetween, or to place therein pillows, bed clothes, or any other desired articles.

I claim:

1. In a davenport bed, a pair of separate coil spring supporting frames, means for mounting the frames one above the other, said means comprising a pair of members pivoted at each end of the upper frame, another pair of members having means forming a pivotal and sliding connection at each end of the lower frame, a fixed support to which the pairs of members are pivoted at their lower ends, means connecting one member of each pair to raise the lower section when the upper section is moved outwardly, and a member having a fixed pivotal connection in the fixed support at one end and in the lower frame at the other end to produce a predetermined

sliding movement of the lower frame along the pivots of its supporting members.

2. In a davenport bed, a raisable rear section, comprising a frame having a pair of slots in each end, a support for each end of the frame, a pair of members each having means forming a pivotal connection with the support and a pivotal and sliding connection with the end slots of the frame, a link for operating the members of the pair in unison, means connected to one of the members for raising the frame by rotation of the members in the support, and a controlling member having a pivotal connection with the support and with the frame for producing a predetermined sliding movement of the frame along the pivots of the members connected thereto.

3. In a davenport bed, a pair of coil spring supporting frames, a support at each end of the frames, means for mounting the uppermost frame to swing outwardly in front of the support, means for mounting the lowermost frame to swing upwardly in the support, a connection between the mounting means of the frames for causing the lower frame to move upwardly when the upper frame is swung in front of the lower frame, and controlling means pivoted to the support and to the end of the lower frame for producing a forward movement of the frame with respect to the support when the frame is raised.

4. In a davenport bed, a pair of end supports, a pair of separate coil spring supporting frames, means for mounting the frames in the supports one above the other, said mounting means including levers for swinging the uppermost frame to one side of the other frame, a pair of levers having a pivotal and sliding connection with the lower frame, and a pivoted connection with the supports for raising the lower frame with respect to the support, a link connecting the levers at each end of the lower frame, a link connecting one lever of each of the frames so that the movement of the upper frame will cause a raising and swinging movement of the lower frame, a cross rod to which the corresponding levers of one of the frames are fixedly connected so that the levers at the opposite ends will be operated in unison, and means for producing a predetermined sliding movement of the lower section upon its connection with its supporting levers when it is raised.

5. In a davenport bed, a pair of end supports, each comprising a cross piece and upright standards at the ends, a pair of spring supporting frames, pairs of supporting frame levers pivoted in the cross pieces for supporting the frames one above the other, positive means connecting one lever of each frame for moving the lower frame upwardly in alignment with the other frame as the latter is swung forwardly, the levers for the lower frame having a loose connection there-

with, a controller pivotally attached to the cross piece and to the corresponding end of the lower frame to produce a limited forward and rearward sliding movement due to the said loose connection, a support for the upper section automatically operable when it is moved in front of the other section and counter balance springs for each end of the frames connected to the standards at the end of the cross piece, one spring being in tension while the other is inoperative to assist in folding and unfolding the sections and to cushion their return to their limiting positions.
